UNITED STATES PATENT OFFICE.

DAVID KENNEDY, OF SOUTH NORWOOD, LONDON, ENGLAND.

FUSE FOR PROJECTILES.

1,310,350.

Specification of Letters Patent. Patented July 15, 1919.

Application filed October 31, 1918. Serial No. 260,583.

To all whom it may concern:

Be it known that I, DAVID KENNEDY, a subject of the King of England, residing in South Norwood, London, England, have 5 invented certain new and useful Improvements in Fuses for Projectiles, of which the following is a specification.

This invention relates to fuses of the type provided with a safety-bolt or other safety- 10 member which moves laterally in relation to the fuse to arm it, but is normally retained in the safety position by a movable retaining-member (hereinafter called the retainer) provided with a lock, its engagement with 15 which is released by set-back.

A primary object of the invention is to provide retaining mechanism adapted to be applied to the body and some of the existing parts of a well-known existing type of 20 fuse, and to provide improved means of release for the safety-bolt thereof in substitution for the releasing means heretofore usually employed.

To this end, retaining mechanism according 25 to the present invention comprises a retainer in the form of a plate adapted to be so hingedly attached (for example about an axis transverse to the direction of projection of the projectile) to the fuse as to 30 move under set-back to become free to swing about its hinge and arm the fuse. Conveniently, the hinged attachment of the retainer is in the form of a pin-and-slot construction permitting the said movement 35 under set-back by means of the slot and the said swinging movement about the axis of the pin. Preferably, the retainer is external to the fuse and its said swinging movement takes place in a direction to cause 40 it to project radially outward from the fuse or substantially so.

Another object of the invention is to prevent the retainer from being moved accidentally when the fuse is handled. To this 45 end, according to the invention, the retainer is used in combination with a cover for it hinged about an axis substantially parallel to (for example the same as) that of the retainer, this cover being normally in such a position as to prevent the retainer from 50 being moved longitudinally by handling it after a security-pin has been withdrawn. Preferably, the retainer and cover are constructed to engage one another in such a 55 manner as to prevent pivotal movement of the cover when the retainer is in its normal

position but to permit such movement when the retainer has been moved under set-back. The retainer, as described above, may have a rigid or yieldingly (for example resili- 60 ently) supported projection upon that face of the retainer which is in contact with the safety-bolt of the fuse. Another object of the invention is to provide that the length of the retainer and the situation of its hinge 65 are so chosen in relation to one another and to the position they will occupy within the gun that the retainer will engage the wall of the gun so as to be prevented thereby from swinging about its hinge sufficiently 70 to arm the fuse.

To these and other ends, the invention consists in the construction, arrangement and combination of parts described hereinafter and pointed out in the claims. 75

The terms herein employed to denote position and direction, such for example as "forward," "rearward" and "lateral" are so used considered in relation to the direction in which the projectile is discharged. Thus 80 the "forward" end is the end that is forward at the moment of projection, and so on.

One embodiment of the invention and a modification thereof will now be described by way of example with reference to the 85 accompanying drawings, wherein—

Figure 1 is a front elevation of an improved fuse to which one form of retainer according to the invention is applied;

Fig. 2 is a central longitudinal section on 90 the line 2—2 of Fig. 1;

Fig. 3 is a side elevation of the parts shown in Fig. 1;

Fig. 4 is an elevation of the retainer, and

Fig. 5 is a bottom plan view of the fuse 95 and retainer as shown in Fig. 1.

Fig. 6 is a sectional elevation showing the fuse mounted on a projectile in the barrel of a gun, and Fig. 7 is a bottom plan view of the fuse provided with a modified form of 100 retainer.

Like reference letters designate like parts in all the figures.

Referring first to Figs. 1 to 5, A is the body of a fuse, described hereinafter, provided with the usual safety-bolt B adapted, after the projectile has been discharged, to be ejected laterally from the body of the fuse. A coiled spring C in compression is provided to effect this. 105

In order that the safety-bolt may be retained in position, this invention provides 110

a support in the form of a sleeve D of metal surrounding the body of the fuse formed with laterally-projecting lugs or cheeks D¹. The inner edges of these cheeks are turned 5 over as seen most clearly in Fig. 5 at D². A retainer is provided in the form of a plate F having stamped-up lateral flanges G slotted at G¹, and also having at one end laterally-projecting tongues F¹. The flanges 10 G do not extend rearward beyond the points G² for a reason which appears hereinafter. This plate is mounted by its slots G¹ upon a pivot-pin E within the channel between the cheeks D¹, the parts being so 15 proportioned that the tongues F¹ are in register with the overturned edges D² of the cheeks when the plate is so situated that the pin E is at the rearward end of the slots G¹. Preferably a projection, as shown at J in 20 Fig. 2, is formed on the side of the plate F which is toward the body of the fuse. This projection may be formed by punching or otherwise deforming the metal.

Mounted upon the outer ends of the pin 25 E where it projects through the cheeks D² is a safety-shutter H, movable therefore about the same pivotal axis as that about which the plate F is movable. The shutter has overturned edges H¹ and a security-pin 30 L is provided to engage these and the cheeks D¹ to lock the shutter during ordinary transit. Furthermore, the overturned edges of the shutter are cut so as to leave the resultant ears H² to cause the shutter 35 to engage the outer faces of the cheeks with light friction. The sleeve D is pierced at K to allow the safety-bolt B to pass freely through it, the hole K being in register with the usual hole provided in the 40 side of the body A for the safety-bolt.

The fuse illustrated in the drawing to which the above described safety mechanism is applied comprises the usual striker N having a head N¹ which is guided in the 45 body A of the fuse and carries the usual ball O under the screw-on top plate P of the fuse. The detonator-holder Q rests as usual on an internal shoulder in the body A. Slidable in the body A between this detonator-holder Q and the head N¹ of the striker pin is a U-shaped or cup-shaped guide R for the striker N. As clearly shown in Fig. 2, the bottom of this guide is pierced and has a projecting rim R¹ to receive and guide 50 the striker N, and the side wall of the guide is pierced to allow the safety-member B to pass through it. A ring T which is also pierced in its wall to receive the safety-member B is provided in the guide R and in 55 this position extends to meet the head N¹ of the striker. A compression spring S surrounding the striker N is arranged between the underside of the head N¹ and the bottom of the guide R. When the projectile 60 to which the fuse has been fixed is fired,

the safety-member B is released in the manner described hereinafter, and the spring S seats the guide R on the detonator-holder Q, the ring T being released from engagement by the safety-member at the same time. 70 Consequently, on the projectile striking the target, set-back acts either on the detonator-holder Q and the guide R and drives them forward against the action of the spring S until the detonator is struck by the pin, or 75 on the ball O and causes the head N¹ of the striker to move toward the rear against the action of the spring S until the pin strikes the detonator.

In the modified form of retaining mechanism shown in Fig. 7, the overturned edges H¹ forming sides of the shutter are provided with grooves H³ in register with slots cut, as shown at D⁴, in the cheeks D¹ with which longer tongues F² on the retainer F 85 can engage to interlock the shutter with the retainer so that the shutter cannot move radially unless the retainer is in its extreme rearward position. Alternatively, the grooves H³ may be omitted, in which case 90 the tongues F² will be only so long that they will extend into, but not through the slots at D⁴ in the cheeks D¹.

In use, the fuse is prepared for the projectile, for example a bomb, in the usual way, the safety-bolt being inserted as shown in Fig. 2 between the striker N and the cup R. The retaining-plate F is swung down about its hinge E so as to hold the safety-bolt B in position against the effort of the 95 spring C to eject it and the plate is then slid upward as viewed in Fig. 2, into the position shown in Fig. 2, so that the tongues F¹ engage the overturned edges D² of the cheeks, thus preventing outward movement of the 100 plate F about its pivot-pin E. The shutter H is then swung down into position and secured there by the security-pin L. If the shutter H is arranged as described above with reference to Fig. 7 it is to be interlocked 105 with the plate F, then the shutter will be swung down together with the plate about the pin E, and on sliding the plate upward its tongues F² will enter into the grooves H³ in the sides of the shutter as well as into the 110 slots in the cheeks D¹. Immediately before use, the security-pin L is withdrawn and when the piece is fired, set-back causes the 115 plate F to move rearward relatively to the surrounding parts, that is to say downward as viewed in Fig. 2, so bringing the tongues F¹ clear of the edges D². The movement is, however, checked when the pin E engages the forward end of the slot G¹ and the plate F flies outward under the 120 influence of the spring C, which latter flings both the plate F and the shutter H outward about the pin E and also ejects the safety-bolt clear of the piece.

The projection at J on the plate F consti- 125

tutes a stop and serves to prevent the displacement of the plate under ordinary jars such as arise in handling; the side flanges G of the plate terminate at their rearward end 5 at the point G² shown in the drawing and thus afford edges which engage the security-pin L and effectually prevent displacement of the plate either longitudinally or pivotally during transit. The forward ends of 10 the cheeks D¹ are perfectly bridged by a closing piece seen at D³ in order that this piece, together with the shutter H, shall serve to impede the entry of mud through the hole K after the bolt B has been ejected. 15 It is to be noted that owing to their pivotal mounting and owing to their being secured to the fuse by such mounting, neither the shutter H nor the plate F is left behind in the gun nor does either tend to foul the 20 side of the gun during the passage of the projectile through the barrel, since any contact with the side of the gun that may possibly occur, is a wiping and not a jamming contact. As shown in Fig. 6, the length of 25 the shutter H and of the retainer F and the situation of their hinge E are so chosen in relation to one another and to the position they will occupy within the barrel V of the gun that the retainer will engage the wall of 30 the gun so as to be prevented thereby from swinging about its hinge sufficiently to arm the fuse fixed on a bomb W that is being fired from the gun.

An important feature of the present invention is that the retaining mechanism comprising the sleeve D and parts carried upon it may be made up and applied to the existing body A of a known fuse without alteration to the body or its internal parts, 35 and the scope of this invention extends to the manufacture of the sleeve and the parts secured to it as constituting a retaining device thus readily applicable to an existing article. It is further to be observed that 40 the retainer is so constructed and situated that it can be seen at a glance whether or not the fuse is armed.

What I claim as my invention and desire to secure by Letters Patent is:—

50 1. In retaining mechanism for the safety-member of a fuse, the combination with a support adapted to be mounted on the fuse, of a retaining plate which is mounted to rock about the support and is normally engaged thereby to retain the safety-member in its operative position, said plate being adapted to move under set-back clear of the part of the support normally engaging the same to become free to rock and thereby release the safety-member.

55 2. In retaining mechanism for the safety-member of a fuse, the combination with a support adapted to be mounted on the fuse, of a retaining plate which is mounted to rock about and to slide relatively to the support

and is normally engaged thereby to retain the safety-member in its operative position, said plate being adapted to slide under set-back clear of the part of the support normally engaging the same to become free to rock and thereby release the safety-member and arm the fuse.

3. In retaining mechanism for the safety-member of a fuse, the combination with a support adapted to be mounted on the fuse, of a pin mounted on the support at right-angles to the longitudinal axis of the fuse, and a retaining plate which is mounted at one end to rock about and to slide relatively to said pin and has its other end adapted to abut against the support to retain the safety-member in its operative position, said plate being adapted to slide under set-back clear of the part of the support normally coacting with the same to become free to rock and thereby release the safety-member.

4. In retaining mechanism for the safety-member of a fuse, the combination with a support adapted to be mounted on the fuse, of a retaining plate which is mounted to rock about the support and is normally held thereby to retain the safety-member in its operative position, and a cover for the retaining plate mounted to rock on said support, said plate being adapted to move under set-back clear of the part of the support normally coacting therewith to become free to rock and thereby release the safety-member.

5. In retaining mechanism for the safety-member of a fuse, the combination with a support adapted to be mounted on the fuse, of a pin mounted on the support at right-angles to the longitudinal axis of the fuse, a retaining plate mounted at one end to rock about and to slide transversely of said pin, and a cover for the retaining plate having one end pivotally mounted on said pin, the other end of said retaining plate being adapted in one extreme position to engage the other end of said cover and said support and thereby retain the cover and the safety-member in their normal positions, said retaining plate being adapted to slide under set-back into its other extreme position clear of the support and the cover and thereby release the safety-member.

6. In retaining mechanism for the safety-member of a fuse, the combination with a support adapted to be mounted on the fuse, of a retaining plate which is mounted to rock about the support and is normally held thereby to retain the safety-member in its operative position, said plate having a projection constituting a stop located in operative relation to the safety-member when the plate is in its normal retaining position, and said plate being adapted to move under set-back clear of the part of the support normally holding the same to become free to rock and thereby release the safety-member.

7. In retaining mechanism for the safety-member of a fuse, the combination with a support adapted to be mounted on the fuse, of a retaining plate which is pivotally mounted to rock about the support and is normally engaged thereby to retain the safety-member in its operative position, said plate being adapted to move under set-back clear of the part of the support normally engaging the same to become free to rock and thereby release the safety-member.
- 10 8. The combination, with a projectile-fuse having a spring-pressed safety-member projecting through the body thereof, of a support mounted on the body of the fuse, a plate-shaped retainer which is mounted to rock about the support and is normally engaged thereby to retain the safety-member in its operative position, said retainer being adapted to move under set-back clear of the part of the support normally co-acting with the same to become free to rock and thereby release the safety-member.
- 15 9. The combination, with a projectile-fuse having a spring-pressed safety-member projecting through the body thereof, of a support mounted on the body of the fuse, a retaining plate which is pivotally mounted to rock about and to slide relatively to the support and is normally engaged thereby to retain the safety-member in its operative position, said plate being adapted to slide under set-back clear of the part of the support normally engaging the same to become free to rock and thereby release the safety-member.
- 20 10. The combination, with a projectile-fuse having a spring-pressed safety-member projecting through the body thereof, of a support mounted on the body of the fuse, a pin mounted on the support at right-angles to the longitudinal axis of the fuse, and a retaining plate mounted at one end to rock about and to slide transversely of said pin and having its other end adapted to abut against the support to retain the safety-member in its operative position, said plate being adapted to slide under set-back clear of the part of the support normally coacting with the same to become free to rock and thereby release the safety-member.
- 25 11. The combination, with a projectile-fuse having a spring-pressed safety-member projecting through the body thereof, of a support mounted on the body of the fuse, a retaining plate which is mounted to rock about the support and is normally engaged thereby to retain the safety-member in its operative position, and a cover for the retaining plate mounted to rock on said support, said plate being adapted to move under set-back clear of the part of the support normally engaging the same to become free to rock and thereby release the safety-member.
- 30 12. The combination, with a projectile-fuse having a spring-pressed safety-bolt projecting through the wall of the body thereof, of an annular support mounted on the body of the fuse and having two projecting cheeks situated one at each side of the end of the safety-bolt, a pin mounted in said cheeks at right-angles to the longitudinal axis of the fuse, a retaining plate having lugs at one end and slots in over-turned sides at the other end mounted on said pin which extends through said slots, and a cover for the retaining plate having one end pivotally mounted on said pin, said lugs in one extreme position of said plate bearing against said support and thereby retaining the safety-bolt in its operative position, and being adapted to move under set-back into another extreme position clear of the support and thereby release the safety-member.
- 35 13. The combination, with a fuse comprising a hollow cylindrical body, a detonator-holder seated in one end thereof, a top plate screwed into the other end thereof, a striker pin having a head slidable in the body, and a ball located between the head of the striker pin and said top plate, a guide for the point end of the pin pierced in its bottom to receive and guide the pin and having a hole in its side wall, a spring in compression between the under side of the said head and the bottom of said guide, and a spring-pressed safety-member extending from inside said guide through the body of the fuse to outside the latter, of a support mounted outside the body of the fuse, a retaining plate which is mounted to rock about the support and is normally engaged thereby to retain the safety-member in its operative position extending through said guide, said retaining plate being adapted to move under set-back clear of the part of the support normally engaging the same to become free to rock and thereby release the safety-member.
- 40 14. The combination, with a fuse comprising a hollow cylindrical body having a hole in the side wall thereof, a detonator-holder seated in one end thereof, a top plate screwed into the other end thereof, a striker pin having a head slidable in the body, a ball located between the head of the striker pin and said top plate, a cup-shaped guide pierced in its bottom to receive and guide the pin and having a hole in its side wall,

a ring located in said guide and having a hole in its side wall, a spring in compression between the under side of said head and the bottom of said guide, and a spring-pressed safety-member extending through said holes, of a support mounted outside the body of the fuse, a retaining plate which is mounted to rock about said support and is normally engaged thereby to retain the

safety-member in its operative position in 10 which it extends through said holes, said plate being adapted to move under set-back clear of the part of the support normally engaging the same to become free to rock and thereby release the safety-member. 15

In testimony whereof I affix my signature.

DAVID KENNEDY.
